UNITED STATES PATENT OFFICE.

HENRY W. SHEPHARD, OF BROOKLYN, NEW YORK.

SHOE ATTACHMENT.

SPECIFICATION forming part of Letters Patent No. 587,335, dated August 3, 1897.

Application filed March 10, 1896. Serial No. 582,606. (No model.)

To all whom it may concern:

Be it known that I, HENRY W. SHEPHARD, a citizen of the United States, residing in Brooklyn, Kings county, in the State of New York, have invented a certain new and useful Improvement Relating to Shoe Attachments, of which the following is a specification.

The present invention is designed to aid in retaining the foot of a bicyclist upon the pedal when it rises. It also permits the rider to lift on the pedal with the upward motion of the foot. These ends are attained without the ordinary unsightly toe-clips, allowing the instant disconnecting of the foot by the ordinary rearward movement thereof, which movement for disconnecting becomes instinctive with bicycle practice.

My device includes a socket-piece attached firmly to the rider's foot. It is fixed to the sole of the shoe or boot between the heel and the ball and so formed as to provide a shallow pocket between this plate and the sole proper having considerable extension front and rear, 25 open at the front, and arranged to receive by a forward movement of the foot a short rigid tongue provided at the rear of the bicycle-pedal. The said plate may be of a breadth a little less than the sole of the shoe and of 30 such length that when its rear edge presses firmly against the front of the heel-lift of the shoe its front edge is just sufficiently in rear of the ball of the foot to properly receive the tongue. The rider being assumed to mount 35 in any ordinary method is certain to find the pedal in a certain position by reason of the superior gravity of the rear edge. Trial has demonstrated that it is easy to place the toe on the pedal as thus presented and give it a 40 partial roll forward and then by sliding the foot forward on the pedal to engage the tongue strongly in the pocket of the plate.

The accompanying drawings form a part of this specification and represent what I consider the best means of carrying out the invention.

Figure 1 is a side elevation. Fig. 2 is a plan view from below. Fig. 3 is a central vertical section of a portion. Fig. 4 is a transverse 50 section of a portion on the line 4-4 in Fig. 1. Figs. 5 and 6 are plan views from below, showing modifications of certain portions.

Similar letters of reference indicate corresponding parts in all the figures where they appear.

Referring to Figs. 1, 2, 3, and 4, A is one of the crank-pins or pedal-shafts of a bicycle, and B a rat-trap pedal mounted thereon and adapted to receive the pressure of the foot in the descent and impel the machine. So far as yet described the parts are of the ordinary and long-approved construction.

D is the tongue, sufficiently thick to afford the requisite strength and stiffness, and D' is an extension downward therefrom by which it is firmly bolted to the rear face of the pedal. E is a bolt, and F a nut by which this tongue-piece is thus stiffly and it may, if desired, be permanently secured to the pedal.

G is the shoe of the wearer, and G' a fairly stout and substantial sole, presenting a sufficiently thick and firm edge to allow it to be strongly seized by clamps.

G² is the heel-lift, which may be shallow, as is generally considered preferable for bicycle-shoes.

M is a plate of steel or other strong metal designed to be secured between the heel and ball of the wearer's foot, said plate having its front edge retreating rearward at the mid-width and the adjacent portion sufficiently depressed below the main body to provide a pocket m between this portion of the plate and the sole of the shoe. The rear edge of this plate M is adapted to press firmly against and to sink a little into the front edge of the heel-lift G². A hole m' is punched or otherwise produced through the plate at or near the rear end of the pocket m, which facilitates the discharge of any dirt which may chance to be received when the wearer walks without removing these attachments.

P are clamps arranged to be forcibly drawn together in transverse ways in the plate M and each adapted by a properly-formed upright arm P' to engage strongly with the sole G'. The inner end of each clamp extends downward and is tapped to receive the proper corresponding portion of a right-and-left screw R, which is adapted to be strongly turned by a proper key (not shown) fitting on either squared end.

U U are rivets firmly set in corresponding holes in the plate M and extending through the

sole G' to give a still more reliable fastening of the plate M to the shoe, so that it shall constitute a unit therewith.

In mounting the bicycle the rider is certain 5 to find the rear edge of each pedal down, the pedal being held in that position by the gravity of the tongue. A movement easily acquired turns the pedal a quarter-revolution and receives the tongue D deeply and strongly 10 in the shallow horizontal pocket m. Now he proceeds in all respects as with the ordinary toe-clip, holding the foot with the toe a little elevated when he has occasion to lift on the pedal, as in climbing a hill or in pulling 15 through deep sand. In dismounting, either rapidly or leisurely, he inclines the foot with the toe downward, and the lifting motion liberates the engagement.

The invention affords marked advantages 20 over any of the ordinary forms of engagement by toe-clips, being less cumbrous in appearance and more firm and reliable in service. The lifting force of the foot, instead of being concentrated on a wire or other device 25 pressing on the toes, is applied through the whole of the front portion of the shoe. There is none of the springing and yielding due to the ordinary clip. It is lighter and is much less conspicuous than the ordinary arrangements. 30 It is less liable to involve dangerous complications in case of collisions, falls, or other accidents.

It will be noted that the form of strong plate M is such that it can be readily secured 35 to the under surface of the shoe-sole at a point intermediate of the heel and ball portion thereof. Such location, while permitting the socket m on the plate to perform its complete function of receiving the tongue 40 and holding the same strongly to the foot, will make no interference with the ordinary walking movements of the wearer, because it lies entirely above the line joining the ball of the foot with the heel.

45 By providing the pedal with the rearwardly-extending tongue of the rigid character described the mere entrance of the same within the socket m of the plate M will be sufficient to effect a satisfactory engagement 50 and allow the pedal to be lifted as well as depressed by the strength of the rider without preventing its immediate detachment by a rearward movement of the foot when required in any emergency. The interior of the socket 55 m is so rounded that when the foot is in normal working position the tongue will properly bear within the socket, but the turning of the foot laterally will have the effect of working the tongue out of engagement.

60 The special contour of the plate M, and particular location of the same on the foot, in-

sures a socket having a forward dip, as shown in Fig. 1, permitting the ready and certain engagement of the tongue D when desired.

The rearwardly-extending tongue D', carried on the pedal, should be short, but it is important that it be given a sufficient length, and that the socket be of sufficient length to allow it to act somewhat leverwise when the strength of the rider is applied to lift as well 65 as depress on the pedal, as is frequently required in emergencies, as in traversing through sand or mounting steep places, or more particularly where both these conditions come together. The pedal turning on 70 an axis under the ball of the foot and the tongue engaging in a socket not directly over it, but farther rearward, it follows that the lifting force of the foot applied through the socket will tend to revolve the pedal on its 75 axis, allowing the tongue to extend upward and to be thrown out of engagement. The length of the socket forward and backward engaging a corresponding length of the tongue allows that tendency to be resisted. The rider 80 by depressing his heel and raising the toe retains the tongue reliably and allows it to be operated on leverwise and to exert a powerful lifting force on the pedal.

Modifications may be made without departing from the principle or sacrificing the advantages of the invention. Parts of the invention can be used without the whole. I can omit the rivets and depend on the clamps alone. Fig. 5 shows such an arrangement. 95 I can omit the clamps and depend on the rivets alone. Fig. 6 shows such a construction.

I claim as my invention—

1. The within-described shoe-plate for bicyclists' use, the same being shaped to match 100 the wearer's sole between the heel and ball of the foot and presenting the forwardly-opening socket m having sufficient length to act leverwise on the tongue received, together with suitable fastening means for securing 105 such plate to a shoe, all substantially as herein specified.

2. In a pedaling attachment for bicyclists the combination with the plate M, having the long socket m and adapted for attachment to 110 the shoe between the heel and ball of the foot, and provided with screw-clamps P, P, of a bicycle-pedal B, having a rigid tongue extending rearward and adapted to engage the plate, substantially as herein specified. 115

In testimony that I claim the invention above set forth I affix my signature in presence of two witnesses.

HENRY W. SHEPHERD.
